(57) CLAIM

The ornamental design for footwear, as shown and described.

DESCRIPTION

FIG. 1 is a perspective view of footwear showing my new design; and,

FIG. 2 is a side view thereof.

The broken line showing in the figures is for illustrative purposes only and forms no part of the claimed design.

Any surfaces, or portions of surfaces, that are not shown form no part of the claimed design.

1 Claim, 2 Drawing Sheets
